UNITED STATES PATENT OFFICE.

FREDRIK LJUNGSTRÖM, OF LIDINGÖ-BREVIK, SWEDEN, ASSIGNEE TO AKTIEBOLAGET LJUNGSTRÖMS ANGTURBIN, OF STOCKHOLM, SWEDEN, A CORPORATION.

REGENERATIVE AIR PREHEATER.

Application filed August 3, 1922, Serial No. 579,543, and in Sweden September 1, 1921.

This invention relates to regenerative air preheaters. In regenerative air preheaters in which a rotor containing a heat absorbing and heat rejecting material herein-
5 after called, for ease of description, "re-
generative mass", rotates continuously or in-
termittently within two channels through
which gases pass, one of which is warmer
than the other, whereby heat is transferred
10 from the warmer gas to the cooler one, the
drawback is met with that there is a trans-
fer of the gas accompanying the regener-
ative mass from one channel to the other.
In my application Serial No. 460,600 for
15 Letters Patent a regenerative air preheater
is disclosed in which a tight joint at the
partitions between the channels is obtained
by the use of sector plates of such a size
that they entirely cover one of the sections
20 into which the regenerative mass is divided.
As disclosed in that application such a sec-
tion passes from one channel to the other
the sector plates on either end of the regen-
erator rotor simultaneously cut off this sec-
25 tion containing regenerative mass. When
so cut off this section contains gas enclosed
between the sector plates such gas being of
the same nature as the gas present in the
channel from which the said section is just
30 about to move. This transfer of gas is par-
ticularly inconvenient when the regenerator
is used as an air preheater for boilers or
the like, in that flue gases are thereby trans-
ferred to the fresh air.
35 The present invention comprises means
for preventing such a transfer of gas from
one channel to the other and consists in ar-
ranging the walls of the rotor, the partitions
between the channels for air and gas, and
40 the sector plates in such position relative
to each other that fresh air may pass during
the rotation into the channel for flue gases
through that section of the rotor which is
just about to pass into the air channel. This
45 is preferably attained by displacing the
sector plates with respect to one another,
and a sufficient amount of scavenging air
is obtained by maintaining constant the re-
lation between the speed of the driving
50 means which rotates the air preheater and
that of the driving means for the fans which
force the gases through the air preheater
and by maintaining a higher pressure in the
air channel than in the gas channel.
55 The invention is illustrated in the accom-
panying drawings in which Fig. 1 shows dia-
grammatically one embodiment which is
represented in Figs. 2, 3, 4 and 5 as applied
in actual practice. Fig. 2' being a longi-
60 tudinal section taken on line 2—2, Fig. 3
with the rotor and other parts in eleva-
tion, Fig. 3 a plan view thereof, Fig. 4, a
cross-section of part of the rotor taken on
line 4—4 of Fig. 5 and Fig. 5, a plan view
65 of part of the rotor. Fig. 6 shows dia-
grammatically another embodiment.
In the embodiment illustrated in Figs. 1—5
inclusive, reference character 1 designates
the rotor of the regenerator. The rotor is
70 divided into compartments such as 2, 3 and
9 by means of walls 13, which are prefer-
ably situated radially of the rotor. Regen-
erative mass 12 is placed in the said com-
partments. By way of example, I have
75 shown, as one form of regenerative mass ca-
pable of use with my invention, alternately
disposed substantially straight and corru-
gated plates, although it is to be understood
that any type of regenerative material may
80 be used. The regenerative material is de-
scribed and claimed in my co-pending ap-
plication Serial No. 460,600 above referred
to. As shown in Fig. 4, walls 13 extend
the full height of the rotor but the plates of
85 the regenerative mass 12 do not extend the
full height but are so arranged that a space
is left at the top and bottom extending across
the whole of each compartment, the purpose
of which will be apparent as the descrip-
90 tion proceeds. The rotor rotates in the di-
rection of arrow 8.
Partitions 4, 5, 6 and 7 serve to separate
the channels 16 and 17 for air and flue gases
respectively. In the embodiment shown in
95 the air passes upwardly on the left hand
side and the flue gases downwardly on the
right hand side, as indicated by arrows. At-
tached to the partitions are sector plates
10 and 11. These sector plates are indicated
100 by shaded surfaces in Fig. 1. Each sector
plate is of such a size that it covers one com-
partment of the rotor and fits snugly to the
edge of the rotor. In previous constructions,
these sector plates were placed directly op-
105 posite each other with respect to the rotor.
By so doing, at certain times in the opera-
tion of the regenerator, a whole compart-
ment would be completely blocked off giving
the disadvantage, above pointed out, that a
110 certain amount of flue gases would be car-

ried over in such a blocked off compartment from the flue gas channel to the air channel.

In the embodiment of present invention shown in Figs. 1-5, these sector plates are 5 displaced with respect to each other, on that end of the regenerator rotor where the rotor travels out of the flue gas channel 17 and into the air channel 16, the upper sector 10, with the flow of gases as shown, being in 10 advance of the lower sector plate 11, as regards the direction of rotation of the rotor. That is, the lower open end of any and each 15 sector-shaped compartment is first closed by the lower sector plate 11 and then after further travel of the compartment in the direction of the arrow, the upper open end of the compartment is closed by the upper sector plate 10. By this means, in operation, there will be a time when each compartment is in 20 communication with the flue gas channel on the one hand and the air channel on the other. For example, as shown in Fig. 1, sector plate 10 has not yet closed off the upper opening of compartment 9, whereas 25 the lower opening of compartment 9 has passed beyond that point at which it is entirely cut off by sector plate 11 and is in communication with the air channel. Now at this time, by maintaining a somewhat 30 higher pressure in the air channel than in the flue gas channel, a small amount of air can pass from the air channel, through compartment 9 and into the flue gas channel, carrying the flue gases in the compartment 35 back into the flue gas channel. This is in part effected by the arrangement of the regenerative material in the rotor, which is shorter than the outer cylinder and the walls of the rotor so that there is a space 40 across the whole top and the whole bottom of the compartment, thus permitting air to pass across the whole bottom of the compartment, up through all the passages of the regenerative mass, across the top of the 45 compartment and out into the flue gas channel.

24 and 25 designate fans which are driven together with the rotor 1, preferably by a common driving means such as electric motor 26. The fans are directly connected to the motor shaft and the rotor is driven from the shaft by means of a belt or chain, or in any other way. If the rotor and the fans are driven from separate motors, the speeds 50 of the latter must be controllable in such a manner that the proper relation between the speeds of the driving means is always maintained. The regenerative mass on passing from the flue gases channel to the air channel 55 has its highest temperature and evidently will be somewhat cooled by the scavenging air. However, as this air will subsequently pass through another section of the rotor 1 in the direction of the flue gases, this heat will also be utilized in the same man-

ner as the heat from the flue gases. In order that no more than the requisite quantity of air shall pass through the section to be scavenged, in that an unnecessary vigorous cooling of this section would otherwise take 70 place, care should be taken that no more than a certain quantity of air, depending on the speed of the rotor, will be allowed to pass through the same, and such definite 75 quantity of air is obtained by the driving means of the fans which force air or gases through the rotor and the driving means of the rotor having constant speeds relatively to each other, in such a manner that, for example, on the speed of the rotor being doubled, the speed of the fans will likewise be doubled. By the employment of the fans it is moreover possible to regulate the pressures so that gas will never pass into the air 80 channel. 85

Fig. 6 shows a modification in which the walls 4 and 5 and 6 and 7 which separate the channels for air and flue gases are all situated in one plane. The scavenging effect obtained in Fig. 1 is here attained by 90 the walls between the rotor sections having such oblique positions as to allow air to pass in the direction of the broken line arrow through each rotor section to the flue 95 gas channel while the rotor is rotating. 100

With the arrangements described an increased efficiency is obtained in the regenerator and in the boiler or the like with which it is connected, in that the air is not contaminated in the regenerator. 100

It should be evident that a combination of the structures of Figs. 1 and 6 is conceivable, the rotor being then devised according to Fig. 1 but the partitions 4 to 7 straight as in Fig. 6. This is simply attained by the sector plates 10 and 11 being displaced relatively to one another the same as in Fig. 1. Such an embodiment is obviously comprised in the principle of the invention above set forth it is only considered that the sector plates form part of the partitions. Various other modifications are obvious within the scope of the invention. 110

What I claim as new and desire to secure by Letters Patent of the United States is:— 115

1. A regenerative heater comprising a first channel for a fluid, a second channel for a fluid, a regenerative material, means for effecting a relative motion between said channels and said material and means to pass fluid from the first channel through the part of the material which is about to enter said channel and into the second 120 channel. 125

2. A regenerative heater comprising a first channel for a fluid, a second channel for a fluid, a regenerative rotor adapted to move within each of said channels and means to pass fluid from the first channel 130

through the part of the rotor which is about to enter the first channel and into the second channel.

3. A regenerative heater comprising a plurality of channels for fluids, a regenerative rotor adapted to move within each of said channels and means to pass fluid from one channel to another through the rotor in the opposite direction to the rotation of the rotor.

4. A regenerative heater comprising a plurality of channels for fluid, partitions separating said channels, a rotor adapted to move in each of said channels, walls in said rotor dividing the rotor into compartments, regenerative material in said compartments, said compartments being open at the ends of the rotor, sector plates on the partitions at opposite ends of the rotor adapted to cover said openings, said sector plates being so disposed with respect to said walls that when a compartment passes from one channel to another there is simultaneously a communication between the compartment and each of such channels.

5. A regenerative heater comprising a plurality of channels for fluid, a rotor

adapted to move within each of said channels, walls dividing said rotor into compartments, regenerative material in said compartments, openings in said compartments, a sector plate adapted to close one of said openings in a given position of the rotor with the edge of the sector plate in line with one of said walls, a second sector plate at the opposite end of said compartment so arranged in the said given position that its corresponding edge is out of alignment with said wall.

6. A regenerative heating device comprising a casing, partitions in said casing forming a plurality of channels for fluid, a rotor in said casing, walls in said rotor dividing the same into compartments, regenerative material in said compartments, means to move said rotor through said channels, and means whereby each compartment when it passes from one channel into another is simultaneously in communication with both channels.

In testimony whereof I affix my signature.
